UNITED STATES PATENT OFFICE.

ARNO BOERNER, OF BRIESSNITZ, NEAR DRESDEN, GERMANY.

ELASTIC TIRE FOR VEHICLES.

979,417.

Specification of Letters Patent. Patented Dec. 27, 1910.

Application filed November 24, 1908. Serial No. 464,241.

To all whom it may concern:

Be it known that I, ARNO BOERNER, merchant, a subject of the King of Saxony, residing at No. 27 Meissenerstrasse, Briessnitz, 5 near Dresden, in the Kingdom of Saxony, Empire of Germany, have invented certain new and useful Improvements in Elastic Tires for Vehicles; and I do hereby declare the following to be a full, clear, and exact 10 description of the invention, such as will enable others skilled in the art to which it appertains to make and use the same.

My present invention relates to elastic tires for vehicles, more particularly for automobiles, and consists of tire-units which may be placed one by one into a channeled wheel-rim and interchangeably held therein. Each tire-unit is composed of a rubber-body which preferably consists of two hemispheres integrally connected with each other 20 and carrying between them a fastening-plate.

In the accompanying drawing:—Figure 1 is an elevation of a tire-unit before its attachment to the wheel-rim. Fig. 2 is a similar view of the same tire-unit seated in the wheel-rim, in which the inner half or hemisphere of the tire-unit is compressed, and wherein a sufficient lateral space is provided 30 to permit a lateral swelling out of the inner hemisphere, when the tire-unit is put under full pressure. Fig. 3 is a plan-view of a fastening-plate.

The tire-unit preferably consists of the 35 two hemispheres 2 and 3 integrally connected with each other and held by means of the cross-shaped plate 1 to the wheel-rim 4 made of U-shaped channel-iron. The hemispheres 2 and 3 are composed of an 40 elastic material, such as rubber.

In order to secure or fasten the two hemispheres to the wheel-rim 4, the plate 1 is 45 preferably made of steel and has the shape of a St. Andrew's cross with a central opening 5 for the passage of one part of the rubber-mass which connects both hemispheres in a thorough manner. Other connecting parts of said hemispheres 2 and 3 are situated at 6, 7, 8 and 9 respectively, as will be 50 best seen in Fig. 3, wherein the circular

shape of the hemispheres is indicated by the broken circular line 10. In this manner both hemispheres are thoroughly connected with each other and with the plate 1. The hemisphere 3 lies within the particularly shaped 55 wheel-rim 4 whereas the hemisphere 2 forms a part of the tread of the wheel.

To attach the tire-unit to the wheel-rim 4, the corners of the cross-shaped plate 1 are placed under the inturned flanges 11 60 and 12 of the rim 4 in such a manner that the plate 1 has no side-play within the rim, so that there is no possibility that the rubber-hemispheres 2 and 3 can accidentally leave the wheel-rim. 65

The cross-sectional shape of the rim 4 is so chosen that at both sides of the hemisphere 3 sufficient play is provided at 13 to give the rubber-masses of said hemispheres a chance to swell out or expand to 70 the best advantage and without resistance when the load is supported by the tire-units.

To prevent a too great resilience of the rubber-components of the tire-unit and at the same time make them more suitable 75 for the reception of knocks and blows, the hemispheres which are arranged within the wheel-rim are preferably compressed, which can be accomplished by making the hollow space of the rim 4 less in depth than the 80 height of the lower hemisphere, as shown in Fig. 2.

It is evident that first one and then the other of the hemispheres may be used as a part of the wheel-tread by turning the 85 tire-unit end for end.

This peculiar construction of the wheel-tire permits of the employment of a rubber-mixture wherein a great amount of Para-rubber is contained, by which means the 90 life of the individual tire-units is lengthened very considerably.

I claim—

An elastic tire for vehicles, comprising 95 elastic tire-units, of which each is composed of two hemispherical members integrally connected with each other, a cross-shaped holding plate arranged between said hemispherical members, and inturned flanges on the wheel-rim arranged to grasp over 100

the ends of all plates to compress the inner hemispherical members on the circumferential face of said wheel-rim and to provide free spaces in the rim of the vehicle-wheel
5 for the free lateral expansion of the inner hemispherical members as each tire-unit is compressed by the load.

In testimony whereof I have signed my name to this specification in the presence of two subscribing witnesses.

ARNO BOERNER.
